Inventor:
Frank P. Daughaday

by Geo. N. Goddard, atty.

UNITED STATES PATENT OFFICE.

FRANK P. DAUGHADAY, OF NORTON, MASSACHUSETTS.

BELT BUCKLE.

Application filed February 4, 1926. Serial No. 35,901.

This invention relates to belt buckles, and is intended to provide a construction for the buckle body by which a front or escutcheon plate of precious metal may be secured 5 to a buckle body of harder, more durable, stronger and less expensive metal so as to utilize an ornamental front, while at the same time providing the requisite strength and resistance to wear on the working parts 10 of the buckle, and also making it possible to produce the ornamental effect of an expensive enamel inlay, as will be hereinafter explained.

With such objects in view the present invention comprises, generally speaking, a buckle body embracing front and rearwardly projecting side members, the front being slightly depressed or countersunk from end to end, leaving slightly raised shoulders or 20 ledges at its opposite side, and an escutcheon plate bearing the ornamental design or front mechanically interlocked with the end edges of the body and dimensioned to fit between and lie substantially flush with the retaining 25 edges of the sides. This and other features of the invention will be described hereinafter and defined in the annexed claim.

In the accompanying drawings I have illustrated a construction embodying the 30 principles of this invention, in which:

Figure 1 is a front view of the complete buckle body constructed in accordance with this invention.

Figure 2 is a front view of the body member itself before the escutcheon plate and its 35 backing sheet is applied thereto.

Figure 3 is a longitudinal section on plane 3—3 of Figure 1.

Figure 4 is a central cross section on plane 40 4—4 of Figure 1.

Figure 5 is a view of the rear or back face of the escutcheon plate showing how contrasting backing sheets are applied thereto.

Figure 6 is a perspective of an unperforated front plate having an embossed or engraved pattern.

In the practice of this invention, according to the form illustrated in the drawings, I employ a buckle body comprising a front 50 member 1, and inwardly turned side members or flanges 3, which are usually formed with inturned strap-guiding extensions 4.

The front member, for the greater part of its area and from one end to the other, is depressed slightly to leave opposite side shoulders 55 2, thus forming a shallow recess for the

reception of the escutcheon plate, as best seen in Figure 4.

The escutcheon plate 5 is made of thin metal, such for example as sterling silver, 60 and is punched out or perforated in any form of pattern or design that may be selected. The width of the escutcheon plate from one side edge to the other corresponds to the width of the space between the ledges 65 or shoulders 2 of the body member, while the length (and by length is meant the direction in which the belt passes through the buckle) is somewhat greater than the length of the front part of the body member. 70

As will be noted in Figure 2, the shoudered portions 2 of the front member are slightly longer than the distance between the end edges of the depressed portion of the buckle so as to leave slight end shou- 75 ders 2^a.

Before the escutcheon plate is applied and secured to the body member a backing 6, of thin flexible sheet material, such as celluloid of any desired color or shade, is applied to the back-face of the escutcheon plate, as shown in Figure 5, and when it is desired to have a middle initial or design of contrasting appearance the central portion of the backing sheet 6 is cut out to allow the application of 85 a smaller backing sheet 7 of contrasting appearance. The backing pieces or sheets are preferably cemented to the back of the escutcheon plate with their back surfaces flush with each other. 90

As shown in Figure 4, the backing sheet may have its exposed portion, seen through the perforations in the escutcheon plate, forced into the perforations of the escutcheon plate so that this portion of the backing lies 95 substantially flush with the exterior surface of the escutcheon plate, in this way giving all the effect of inlay work but at greatly reduced cost since the celluloid, while in a partly plastic condition, may be forced into the openings in the escutcheon plate by a suitably formed die at very little expense as contrasted with the expense of inlay with enamel.

The opposite end edge portions 5^a of the 105 escutcheon plate, after it has been applied with its backing to the buckle, is kept in place by inturning the end edges or attaching lips 5^a. These attaching or interlocking lips 5^a may be partly formed when 110 the escutcheon plate is blanked out, and in that case only a slight crimping of one edge

is necessary to securely lock the escutcheon plate to the front plate, while sidewise removal is prevented by the ledges or shoulders 2 and 2^a.

5 The projection of the shoulders 2 and 2^a is preferably just sufficient to equal the thickness of the escutcheon plate with its backing so that the finished buckle body presents a smooth and flush surface and 10 periphery.

Since the belt-attaching bail forms no part of the present invention I have merely indicated in dotted lines, in Figure 3, the position which it would normally assume.

15 The outward pressing of those portions of either backing sheet subtending the perforations in the escutcheon plate accomplishes two purposes, namely, such portions tend to prevent any displacement of the 20 backing sheets, and furthermore by being pressed outward to a substantially flush position they render the ornamentation more conspicuous beside giving the effect of inlay.

When it is not desired to produce the effect 25 of an enamel inlaid pattern the backing sheet will, of course, be omitted and the

ornamental front plate of precious metal with its engraved embossed pattern, as illustrated in Figure 6, will be applied directly to the buckle body in precisely the same 30 manner as before described, that is, by hooking one of the flanges 5^a of the imperforate plate 5^b, around one end edge of the buckle body and crimping down the opposite flange to interlock with the opposite end edge of the 35 body without the interposition of the enamel backing.

What I claim is:

A buckle body embracing in its construction a front member and rearwardly turned side members, the front member being countersunk from one end edge to the other to leave slightly projecting side ledges, and a separate escutcheon plate provided at its end edges with inwardly bent lips to interlock with the end edges of the buckle body, the escutcheon plate being dimensioned to lie between and engage the side ledges of the buckle body.

In witness whereof, I have subscribed the above specification.

FRANK P. DAUGHADAY.
